UNITED STATES PATENT OFFICE.

NICHOLAS HAYDEN AND CHARLES F. C. WURST, OF ST. PAUL, MINNESOTA.

STOCKING.

SPECIFICATION forming part of Letters Patent No. 615,271, dated December 6, 1898.

Application filed January 22, 1898. Serial No. 667,639. (No model.)

To all whom it may concern:

Be it known that we, NICHOLAS HAYDEN and CHARLES F. C. WURST, citizens of the United States, residing at St. Paul, in the 5 county of Ramsey and State of Minnesota, have invented a new and useful Stocking, of which the following is a specification.

This invention provides simple and easily-operated means for connecting the legging of 10 a stocking to the foot portion and which will admit of the parts being readily separated when required.

A further purpose of the invention is to secure the parts of the stocking by positive and 15 frictional means, thereby preventing creeping of either part and at the same time securing a neat and serviceable joint.

For a full understanding of the merits and 20 advantages of the invention reference is to be had to the accompanying drawings and the following description.

The improvement is susceptible of various 25 changes in the form, proportion, and the minor details of construction without departing from the principle or sacrificing any of the advantages thereof, and to a full disclosure of the invention an adaptation thereof is shown in the accompanying drawings, in which—

Figure 1 is a perspective view of a stocking 30 embodying the essential features of this invention. Fig. 2 is a view similar to Fig. 1, having the parts separated and shown on a larger scale, the upper portion of the legging being broken away. Fig. 3 is a detail section.

Corresponding and like parts are referred 35 to in the following description and indicated in the views of the drawings by the same reference characters.

The stocking comprises the legging 1 and 40 foot portion 2 and is separable on a line corresponding approximately with the ankle or a short distance above the same. The foot portion has loops 3 at its sides, which are designed to pass through slots or openings 4 in 45 the sides of the legging at its lower end. Similar loops 5 are located at the sides of the legging at its lower end and near the rear and are designed to retain an elastic strap or tape 6 in place. This elastic strap or tape 6 may 50 be secured to the lower end of the legging in

any desired manner, but the loops 5 admit of it being easily and quickly removed when required.

When the stocking is worn, the upper end of the foot portion passes within the lower 55 end of the legging and the loops 3 are passed through the slots 4, and the end portions of the elastic strap 6 are slipped through the loops 3, thereby securing the contiguous ends of the separable portions. The end portions 60 of the elastic strap or tape, after being passed through the loops 3, are detachably connected by a hook and eye or any suitable clasp or fastening which will admit of the elastic having its ends quickly and easily separated when required. The end portions of the separable parts are hemmed, thereby providing end ribs, and the overlapping portions pass by each other a sufficient distance to admit of the elastic strap or tape coming between the reinforced or thickened ends of the legging and 70 foot, and after the part 6 is secured about the limb the overlapping portions of the stocking will be held against displacement by reason of the binding action caused by the pressure 75 of the elastic 6 and by the reinforcing ends of the said parts coming in contact with the edge portions of the elastic 6, as will be readily understood.

The means set forth provide for the foot 80 portion of the stocking being readily detached from the legging for any purpose desired, and when the stocking is worn the elastic insures a neat joint and one which will prevent the creeping of the overlapping portions past one 85 another so as to expose the part covered thereby.

From the foregoing it will be understood 90 that the foot portion of the stocking may be readily detached and replaced by another when badly worn or otherwise unfitted for further service at less expense than replacing the entire stocking, and, moreover, foot-pieces of different kinds may be applied to the leg portion, and the parts comprising the stocking 95 may be of knitted goods, silk, felt, leather, or any desired material, and the separable parts may be secured by buckle, hook and eye, button, or other convenient and desirable fastening.

Having thus described the invention, what is claimed as new, and desired to be secured by Letters Patent, is—

1. A stocking comprising a legging and a foot portion having their meeting end portions overlapped, loops applied to one of the parts and passing through corresponding slots or openings in the other part, and a strap or tape encircling and confining the overlapping portions of the stocking and passing through the said loops to prevent their withdrawal through the said slots or openings, substantially as and for the purpose set forth.

2. In a stocking, the combination of a foot portion having loops projecting outwardly from its sides, a legging having its lower end portion overlapping the upper end portion of the foot part and formed with openings or

slots for the passage therethrough of the loops of the foot portion, and an elastic strap or tape having slideable connection with the lower end portion of the legging and adapted to pass through the side loops of the foot portion and prevent their withdrawal through the slots of the legging, said strap encircling and confining the overlapping portions of the stocking and provided with means for adjustably connecting their ends, substantially as described.

In testimony that we claim the foregoing as our own we have hereto affixed our signatures in the presence of two witnesses.

NICHOLAS HAYDEN.
CHARLES F. C. WURST.
